2,681,158

TREATING APPARATUS

Karl I. Henrikson, Cleveland Heights, Ohio, assignor, by mesne assignments, to Kaiser Steel Corporation, Oakland, Calif., a corporation of Nevada

Application August 31, 1950, Serial No. 182,601

6 Claims. (Cl. 214—17)

1

This invention relates to an apparatus for cooling heated material. More particularly it is concerned with providing an apparatus which constitutes an improvement over that disclosed in Patent 2,480,726 issued August 30, 1949, and which comprised a rotating, cooling bin designed for cooling material such as coke, cement clinker, burnt lime and the sinter discharged from sintering machines.

As in the case of the apparatus disclosed in Patent 2,480,726 issued August 30, 1949, this invention will be described as one particularly adapted for cooling sinter discharged from a sintering machine, it being understood, however, that within the broader aspects of the invention it may be used for cooling numerous other materials some of which have been referred to above.

One of the primary objects of this invention is to provide novel means for supporting the cooling bin at the center thereof.

Another object of this invention is to provide novel means for supporting the bin along its outer periphery.

Another object of the invention is to provide an annular cooling bin conical in cross section, located along the outer periphery of a wheel like frame.

A further object of the invention is to provide an improved driving arrangement for rotating the bin.

Another object of the invention is to provide a cooling bin having an annular guard mounted above and adjacent the upper extremity of the inner retaining wall of the bin.

A still further object of the invention is to provide novel means separate from the bin structure for retaining the material to be cooled upon the horizontal shelf portion of the bin prior to its removal by a plough or scraper.

These and other objects are accomplished by providing a cooling apparatus generally comprised of a rotatable wheel-like frame consisting of truss-type spokes or segments and adapted to rotate about a vertical axis. A substantially annular bin structure conical in cross section is located along the outer periphery of the frame adjacent the outer extremities of the truss type segments. The bin structure includes a circular, downwardly and outwardly inclined, imperforate, inner partition or wall and a circular, downwardly and inwardly inclined imperforate, outer partition or wall. The inner partition is of substantially greater width than the outer partition. A horizontal, annular, platform or shelf extends outwardly from the base of the inner wall to a

2

point beyond the lower extremity of the outer wall. Means are provided for supporting and rotating the frame, which means include a central bearing member to which the central or hub portion of the frame is removably attached and a plurality of alternately spaced idler and drive wheels circumferentially located below the outer periphery of the frame and adapted to frictionally engage a track mounted on the underside of the frame. Side guards which are separate from the frame are also provided to prevent the material deposited upon the platform from being displaced during a portion of the rotation of the frame. A plurality of ploughs each one of which is positioned at a predetermined point along the outer periphery of the frame and in spaced relationship to one another serve to remove the material deposited upon the platform.

Other objects and advantages will become apparent by reference to the drawings wherein:

Figure 1 is a plan view partly diagrammatic of the improved cooling bin assembly and associated parts.

Figure 2 is a side elevational view partly diagrammatic of the cooling bin assembly and associated parts taken along lines 2—2 of Figure 1.

Figure 3 is a partially sectional, and partially perspective view of the cooling bin.

Figure 4 is a plan view of the idler and drive wheels mounted below and along the outer periphery of the bin.

Figure 5 is an enlarged sectional view of one form of side guard that may be used to hold the material on the horizontal shelf during rotation of the bin.

Figure 6 is another plan view of the cooling assembly; showing the wheel-like arrangement of the parts thereof.

Figure 7 is an enlarged sectional view of the center bearing and supporting members shown in Figure 3.

With further reference to the drawings and particularly Figures 1 and 3 the cooling bin frame consists of a structural steel frame 5 generally comprised of a plurality of spoke-like segments A which extend radially outwardly from the center of the frame. Each segment is in the form of a truss B. Mounted along the outer periphery of the frame at the extremity of the segments A is an annular cooling bin C. The lower, inner extremity of each segment A is joined to a central casting or bearing member D mounted on a suitable base E. The assembly is rotated by means of a plurality of drive wheels F located below the frame.

Each segment A is comprised of a horizontal floor I beam 10 affixed to and extending radially outward from a circular hub or casting member 12. The casting member 12 may be of any suitable configuration. Preferably it is so constructed as to have an outer and annular depending flange portion 14, joined to the wall 16 of the casting's central cup portion 18 by means of a plurality of spoke-like webs 26, which extend radially outward from cup 18 and are integral with the inner wall 16 and flange 14. Each floor I beam 10 is fastened at its inner extremity to the depending flange 14 and top 24 of the casting 12 by means of bolts 20 and 22, the bolts 20 being inserted through the upper flanges of the I beam and the circular cover or top 24 and the bolts 22 being thrust through the depending flange 14 of the casting and rectangular plates 28 which have been previously welded to the upper and lower flanges and web 30 of the I beam 10 on both sides of the beam.

The central cup portion 18 of the casting 12 is provided with an aperture 32 at the bottom thereof of which fits over an upstanding shaft or bearing 34, that has been previously anchored or keyed by a plurality of keys or pins 33 to a steel support 36. This support in turn is secured to a concrete base 38. A circular steel cap or bearing housing 40 fits over shaft 34 within the cup portion 18 and when fastened to casting 12 by bolts 31 serves to secure the hub or casting 12 upon the shaft 34. A roller bearing 42 placed between the inner wall of the cap and the shaft 34 insures freedom of movement of the casting 12 about shaft 34.

Associated with each floor beam 10 are a plurality of diagonal bracing beams 43, 44, and 45 which are secured to the upper flanges or faces of the floor beams. These braces in turn support a horizontal arm 46 of generally I beam configuration, the outer brace 43 also acting as a support for an extension 48 for each arm 46. A depending arm 50 fastened to each extension 48 extends downwardly therefrom in an inwardly direction. The inner extremities of the horizontal arms 46 have their upper and lower flanges or faces bolted to circular plates 52 and 53 respectively. These plates are held together by a suitable locking pin 55. If desired, curved stiffeners 59 may be inserted between and attached to each arm 46 at a short distance outwardly from plates 52 and 53. A circular partition or wall of plate steel 57 is secured upon the upper faces or flanges of the diagonal beams 43 and extends upwardly therealong from the base of beams 43 to an annular guard 58 also of steel plate mounted above the assembly adjacent the point where the diagonal braces 43 join the arms 46. This partition 57 forms an inner retaining wall for the bin and extends in a downwardly and outwardly direction. The portions of the floor beams 10 projecting outwardly beyond bracing beams 43 are likewise covered by steel plate to form an annular horizontal, receiving shelf 60. Cross beams 62 may also be placed between the floor beams at this point to further strengthen the frame assembly at its outer periphery.

Another circular partition 64 of plate steel is secured to the upper faces or flanges of the depending arms 50 and extends downwardly therealong from one end of the arm to the other. This partition forms an inwardly, inclined, outer retaining wall which together with the horizontal shelf 60 and outwardly inclined, inner retaining

wall 57 form an annular cooling bin C, which is substantially conical in cross section, along the outer periphery of the steel assembly 5.

Inclining the outer retaining wall inwardly greatly facilitates the flow of sinter material initially deposited in the bin toward the inner part of horizontal shelf 60, whence it is ultimately removed after having been cooled.

The horizontal shelf 60 may be advantageously lined with a refractory shelf covering 66 conveniently formed of fire bricks, laid thereon in a suitable manner and extending from the base of the inner retaining wall 57 to the outer edge of the shelf 60. A similar refractory covering may also be placed over the inner wall 57, if desired.

Because of the rather sharp inclination of the inner wall 57 and outer wall 64 the material to be cooled will flow rapidly downward through the bin until it becomes deposited upon the horizontal shelf 60.

The sharp inclination of both walls 57 and 64 prevents any great quantity of hot sinter from accumulating along either wall. Since the angle of inclination of both walls is substantially the same a more even flow of the hot sinter material from the top of the bin to shelf 60 will also be effected. As a result the cooled sinter will become more evenly distributed upon the shelf whence it is then removed.

Referring to Figures 3 and 4 the means used for driving or rotating the cooling bin assembly generally comprise 3 or more drive wheels 68, mounted in suitable cradles 70 secured to a concrete base 84. Each drive wheel is coupled to a drive shaft 72 connected to an electric motor 74 through a series of gears and couplings 75. Located between each drive wheel is a series of idler wheels 76, which by means of springs 80 are resiliently mounted in cradle or supporting members 78 secured to the concrete base 84. Similar springs may also be used to resiliently mount the driving wheels 68 and idler wheels 76 are arranged circumferentially, underneath the cooling bin assembly and are adapted to frictionally engage an annular track 82 mounted on the underside of the bin. This track is secured at various points to the lower faces or flanges of relatively short I beams 85, whose upper faces or flanges are secured to steel plates 86, the latter of which extend between and are connected to floor beams 10. This circumferential arrangement of the drive and idler wheels below the outer periphery of the cooling bin assembly permits efficient rotation of the bin. Moreover, these wheels simultaneously serve as supports for the outer section of the assembly, which is subjected to the most weight, since that part of the assembly which comprises the annular cooling bin, is located substantially directly over these wheels.

The springs 80 in the cradles or bearing members 78 and 76 or the wheels allow the wheels to absorb hard impacts and shocks such as may be caused by excessive or uneven loading of the bin at one or more points. As a consequence of this the springs also assist in absorbing various shearing stresses which might otherwise be placed from time to time on the central shaft 34 to which central casting 12 is connected.

The use of a central hub or casting member 12 to which the floor beams 10 are connected, together with the use of circular plates 52 and 53 to which the upper arms 46 are joined results in various sections of the assembly being securely joined together, thereby increasing the rigidity

of the structure as a whole. When all the segments have been joined together in the center as above described each individual segment tends to strengthen and reinforce the others.

Various reinforcing members can also be used, if desired, to further strengthen the assembly such as horizontal bracing beams 88 which may be fastened to the lower flanges of cross beams 62 located below shelf 60. A plurality of supporting and reinforcing I beams 90 may also be mounted between each diagonal bracing beam 43 by being fastened at one end to various struts 92 located between and fastened at each end to a separate diagonal beam 43, and by being fastened at the other end to an I beam 62' located below shelf 60 at the juncture of shelf 60 and wall 57. Similar reinforcing I beams 108 may also be mounted between the depending arms 50 by being fastened at each end to channel shaped stringers 110 and 111.

A channel shaped wearing sleeve or covering 115 which may be formed of cast iron or other suitable material may advantageously be used to cover the extensions 43 on arms 46 to take the wear incident to movement of the sinter thereover, that being desirable since the sinter in many cases is highly abrasive in character.

Any suitable means may be used to supply the material to be cooled to the rotating bin such as by a chute 120. When the material to be cooled is hot sinter a machine or apparatus similar to that disclosed in Patent 2,480,726 may be used for discharging the sinter into the cooling bin.

The sinter material to be cooled is discharged upon the inclined surfaces or walls 57 and 54 and slides or flows downward onto the horizontal shelf portion 60 of the bin. It will be noted that the outer wall 64 is of shorter width than inner wall 57 in order to allow scrapers or ploughs 94 mounted adjacent the bin to remove the cooled material.

In the rotation of the bin the material is air cooled and the lowermost material or the material that has become deposited upon the shelf 60 is removed first.

One or more scrapers or ploughs may be utilized depending upon the amount of material, which one desires to cool and to remove within a given length of time.

When a plurality of ploughs 94 are used to remove the material it is obvious that more cooled material can be removed during a given length of time than would occur if but one plough were used, with the result that more material can be fed to the bin to take the place of that which has been removed. In this way without increasing the size of the bin, its capacity can be increased.

The employment of a plurality of ploughs also permits continuous use of the cooling bin since, if one plough needs repair the others will still remain in operation, and there will be no need to stop the bin during the period of repair.

By placing the ploughs at predetermined spaced points along the outer periphery of the bin and at varying distances from discharge chute 120, the rate of cooling of the sinter can be more efficiently controlled, in the sense that removal of the sinter at different points from the feeder chute by one or more ploughs means that different periods for cooling are employed all of which is dependent upon the net results desired.

Referring to Figure 1 two ploughs are shown. Each plough or scraper is pivotally connected to a post 96 disposed to one side of the bin. Each scraper is adjustable and is held in adjustment

by associated screw adjusting means 97, including the handwheels 98. The scrapers 94 are disposed a short distance above the upper face of the shelf portion of the bin, so as to remove therefrom sinter material or the like resting thereon. The sinter material thus removed is deflected into a hopper 99 associated with each plough. Each hopper is provided with an outlet opening 100 overlying a belt conveyor 101 of any suitable material. The hopper 99 and belt conveyor are located in a pit 130 located beneath the cooling bin assembly which is reached by ramps or stairways 131.

By the time the loose or block sinter is removed from the bin it has been sufficiently cooled so as to avoid the danger of injury to the conveyor and may be then safely handled thereby so as to be transported to a desired point for further treatment or for storage.

If desired a suitable number of spray pipes 149 may be disposed above the main or conical portion of the bin for spraying cooling water upon the sinter or other hot material thereon, to assist in the cooling operation. The particular location of these pipes with respect to the ploughs and/or the machine which initially discharges the hot material into the cooling bin depends upon the particular amount of cooling desired.

In order to restrain the material on the shelf 60 from displacement, during rotation of the bin, a sectionalized annular side guard 102 is mounted along side the bin. Referring to Figures 1 and 5 it will be noted that each section of the side guard is comprised of a channel iron 104. The two flanges 105 of channel iron 104 are welded to a plate 106. This plate is welded or bolted to a backing plate 107 secured to an arm 109 which in turn is fastened to the upper extremity of structural supports 112.

Openings 113 are provided in the side guards to permit the ploughs 94 to be swung inwardly and over the shelf 60.

These side guards prevent the material deposited upon the shelf from being displaced during rotation of the bin until it is removed by the ploughs.

From the above description it will be observed that one of the important advantages resulting from the use of the improved type of cooling bin is the fact that a more even flow of the sinter from the top of the bin to the bottom is effected. This allows a better more even rate of cooling and causes a more equal distribution of the cooled sinter upon shelf 60.

Supporting the assembly at its center through the medium of a central bearing as well as along its outer periphery provides the bin assembly with greater rigidity and strength.

The utilization of an annular guard 58 along the top of the bin assembly prevents the hot sinter which is being discharged into the cooling bin from falling outside of the bin and on the various unprotected elements of the assembly or its associated parts.

It is an important advantage of this invention that material such as sinter blocks can be handled during cooling with a minimum amount of breakage and with very little, or no production of fines. It is another advantage that heated material can be sufficiently cooled before going to a conveyor belt that the latter does not undergo excessive wear, or destruction, by contact with the heated product.

Various changes in the construction and arrangement of the parts may be made in the in-

vention without departing from the spirit or scope thereof and, accordingly, the invention is not to be taken as limited except by the appended claims wherein what is claimed is:

1. In a cooling machine of the character described a rotating bin structure comprised of an annular downwardly and outwardly inclined inner wall and an annular downwardly and inwardly inclined outer wall said inner wall being of substantially greater width than said outer wall, said outer wall providing a continuously unbroken supporting surface from the top to the bottom thereof for the material in contact with the wall, a substantially horizontal refractory lined shelf extending outwardly from the base of said inner wall and beyond the lower extremity of said outer wall, an upright central bearing member to which said rotating bin structure is rotatably and supportingly attached, a peripheral track mounted on the undercarriage of said bin structure, a plurality of drive wheels for frictionally engaging said track, a plurality of idler wheels frictionally engaging said track alternately with said drive wheels, both said drive and idler wheels also serving to support the outer periphery of said bin structure, and means for resiliently mounting said drive and idler wheels.

2. In a cooling machine of the character described a rotating bin structure comprised of an annular downwardly and inwardly inclined outer wall and an annular downwardly and outwardly inclined inner wall said inner wall being of substantially greater width than said outer wall, said outer wall providing a continuously unbroken supporting surface from the top to the bottom thereof for the material in contact with the wall, a substantially horizontal shelf extending outwardly from the base of said inner wall and beyond the lower extremity of said outer wall, an annular guard mounted adjacent the upper extremity of said inner wall, an upright central bearing member to which said rotating bin structure is supportingly attached, a peripheral track mounted on the undercarriage of said bin structure, a plurality of drive wheels for frictionally engaging said track, a plurality of idler wheels adapted to frictionally engage said track alternately with said drive wheels both said drive and idler wheels also serving to support the outer periphery of said bin structure and means for resiliently mounting said drive and idler wheels.

3. In a cooling machine of the character described a rotating bin structure comprised of an annular downwardly and outwardly inclined inner wall and an annular downwardly and inwardly inclined outer wall, said inner wall being of substantially greater width than said outer wall, said outer wall providing a continuously unbroken supporting surface from the top to the bottom thereof for the material in contact with the wall, a substantially horizontal shelf extending outwardly from the base of said inner wall and beyond the lower extremity of said outer wall, an upright central bearing member to which said rotating bin structure is supportingly attached, a track mounted on the undercarriage of said bin structure along the outer periphery thereof, a plurality of drive wheels for frictionally engaging said track, a plurality of idler wheels adapted to frictionally engage said track alternately with said drive wheels, both said drive and idler wheels also serving to support the outer periphery of said bin structure, means for resiliently mounting said drive and idler wheels,

and means for removing the material deposited upon said shelf.

4. In a cooling machine of the character described a rotating bin structure comprised of an annular downwardly and outwardly inclined inner wall and an annular downwardly and inwardly inclined outer wall, said outer wall providing a continuously unbroken supporting surface from the top to the bottom thereof for the material in contact with the wall, a substantially horizontal shelf extending outwardly from the base of said inner wall to a point beyond the lower extremity of said outer wall, an upright central bearing member to which said rotating bin structure is supportingly attached, a track mounted on the undercarriage of said bin structure along the outer periphery thereof, a plurality of drive wheels frictionally engaging said track, a plurality of idler wheels also adapted to frictionally engage said track alternately with said drive wheels, both said drive and idler wheels also serving to support the bin structure, means for resiliently mounting said drive and idler wheels, and means for removing the material deposited upon said shelf including a plurality of plows each one of which is positioned at a predetermined point along the outer periphery of the bin structure in spaced relationship to each other.

5. In a cooling apparatus of the character described, a rotatable wheel-like frame having a hub portion journalled upon an upstanding bearing member and a plurality of truss-type segments extending radially outward therefrom, an annular, downwardly and outwardly inclined inner imperforate partition affixed to the outer extremities of said truss-type segments, an annular, downwardly and inwardly inclined outer imperforate partition of less width than said inner partition also affixed to the outer extremities of said truss-type segments in spaced relationship with said inner partition, said outer partition providing a continuously unbroken supporting surface from the top to the bottom thereof for the material in contact therewith, a horizontal shelf extending outwardly from the base of said inner partition and beyond the lower extremity of said outer partition, whereby a substantially annular bin structure, conical in cross-section, is formed along the outer periphery of said frame adapted to receive the material to be cooled, guard means mounted upon said truss-type segments adjacent the upper extremity of said inner partition, track means located on the underside of said frame adjacent the outer periphery thereof, means including a plurality of drive wheels and idler wheels in contact with said track means for rotatably supporting said wheel-like frame, and means for resiliently mounting said drive and idler wheels.

6. In a cooling apparatus of the character described, a rotatable wheel-like frame having a hub portion journalled upon an upstanding bearing member and a plurality of truss-type segments extending radially outward therefrom, an annular, downwardly and outwardly inclined inner wall affixed to the outer extremities of said truss-type segments, an annular, downwardly and inwardly inclined outer wall of less width than said inner wall also affixed to the outer extremities of said truss-type segments in spaced relationship with said inner wall, said outer wall providing a continuously unbroken surface for the material in contact therewith, a horizontal deck extending outwardly from the base of the

inner wall to a point beyond the lower extremity of said outer wall, whereby an annular bin structure, conical in cross-section, is formed along the outer periphery of said frame, track means located on the underside of said wheel-like frame adjacent the outer periphery thereof, means including a plurality of resiliently mounted drive wheels located circumferentially below said frame and adapted to frictionally engage said track means for rotating said frame, plow means for removing said material from said deck, and means separate from said wheel-like frame for retaining the material deposited upon said deck against

displacement until it is removed therefrom by said plow means.
